CLAIM

The ornamental design for a sound bar, as shown and described.

DESCRIPTION

1. Sound bar

1.1 : Front perspective view

1.2 : Bottom perspective view

1.3 : Front

1.4 : Back

1.5 : Left

1.6 : Top

1.7 : Bottom

1.8 : Reference view

This article is a sound bar speaker capable of connecting various devices, i.e. television, computer; the broken lines shown in reproductions 1.1 to 1.7 depict portions of the sound bar that form no part of the claimed design; a right view is omitted because it is a mirror image of the left view; reproduction 1.8 illustrates a state of use wherein the part in grey shade indicates fabric materials applied to a speaker and forms no part of the claimed design; the shading lines

(Continued)

are used to show the surface of the claimed design and do not represent its surface ornamentation.
